KNIFE CLEANER

Robert Leano, Pasadena, Calif.

Application September 7, 1937, Serial No. 162,573

1 Claim. (Cl. 15—106)

My invention relates to improvements in knife cleaners and the main object is to provide a device which may be conveniently mounted beneath the sink faucet and used to wash, clean, and dry knives of all kinds.

Another object is to provide a device of this kind in simple and durable form made up of spaced parallel bars supported on a bracket for mounting beneath the sink faucet and each bar having on its inner or proximate faces double rows of bristles which meet along the center line at their free ends so that a knife blade inserted therebetween will be cleaned by contact therewith, the outer faces of the bars also carrying rubber strips by which the knife blade may be dried.

With these and other objects in view the invention resides in the novel construction and arrangement of parts as hereinafter fully set forth and claimed, reference being had to the accompanying drawing as showing a preferred embodiment of my invention for purposes of exemplification.

In the drawing:

Figure 1 is a side elevation.

Figure 2 is a plan view.

Figure 3 is a cross section along the line 3—3 in Figure 2.

In carrying out my invention I provide a rectangular frame made up of spaced parallel side bars 5—5a connected and held in this relation by end strips 6—6a secured by screws 7. The said side bars 5—5a are preferably but not necessarily made of wood and along their inner or proximate faces have spaced rows of sockets 8 in which are seated the butts of bristles 9 which extend them from the bars to meet at their free ends along the center or axis of the frame. The outer faces of the side bars have grooves 10 extended longitudinally from end to end opening outwardly. In these grooves are seated rubber strips or squeegees 11 by means of screws 12 with the free margins of the strips extending outwardly some distance from the outer faces of the bars.

A bracket or support rod 13 is secured by one end at 14 to the center of the end strip 6a and extends therefrom coaxially relative to the side bars 5—5a and at its outer end is formed to an eye 15. A brace rod 16 is provided and the same is formed up with an eye 17 and spaced divergent arms 18 terminated at their ends in eyes 19. Hooks or screw eyes 20 are secured to the side bars 5—5a adjacent to the end strip 6. These parts constitute a supporting means for the cleaner and for such use the eyes 15 and 17 are rotatably seated down over a post or pipe 21 so that the cleaner extends horizontally from the post and is supported in this position by the arms 18 which extend diagonally upwardly from

the post to their connection with the hooks 20. To prevent the eye 17 from dropping down the post too far, the post has a shoulder 22.

In use the post 21 is mounted vertically below the faucet of the ordinary sink (not shown) so that the cleaner frame is supported out beneath the faucet. In this position water may run from the faucet directly onto the bristles 9 and by inserting the knife blade between the bristles 10 the blade will be cleaned as will be readily evident, the blade being worked back and forth between the bristles for this purpose. When the blade has been cleaned it may be withdrawn from between the bristles and drawn flatwise across either of the rubber strips 11 which will then wipe off all moisture from the blade leaving it ready for use again. When not in use the cleaner may be swung to one side from beneath the faucet and will not interfere with ordinary use of the sink.

The mounting of the post 21 may be carried out in any suitable manner or in lieu of the use of this post, and where the water pipes are exposed, the mounting means for the cleaner may be placed directly on the pipes.

While I have herein set forth a certain preferred embodiment of my invention it is understood that I may vary from the same in minor structural details so as best to provide a practical device for the purposes intended, not departing from the spirit of the invention and within the scope of the appended claim.

I claim:

In a device of the kind described for mounting upon a vertical post, a brace element having an eye for engaging the post, and a pair of arms extended divergently from the eye for angular extension upwardly from the post as mounted thereon, attachment eyes at the free extremities of the arms adapted to fall in a horizontal plane when the device is mounted, a support rod having at one end an eye for engaging the post at a point above the post engaging eye of the brace element, the free end of the rod extending outwardly from the post in a vertical plane passed through the post on which the device is mounted and bisecting the angle of divergence of the arms of the brace element as mounted on the post, and a brush holding frame supported outwardly upon the eyes of the extremities of the brace arms and inwardly by the free end of the support rod, the frame being thus adapted for horizontal disposition when the device is mounted on the post, the said frame including spaced side bars with means thereon for engaging the attachment eyes of the divergent arms of the brace element, and connecting end strips with means on the innermost end strip for engaging the end of the support rod.

ROBERT LEANO.
